UNITED STATES PATENT OFFICE.

JULIUS A. MAHR, OF MINNEAPOLIS, MINNESOTA.

FOLDING BABY-CARRIAGE.

1,335,122.

Specification of Letters Patent. Patented Mar. 30, 1920.

Application filed November 15, 1919. Serial No. 338,155.

To all whom it may concern:

Be it known that I, JULIUS A. MAHR, a citizen of the United States, residing at Minneapolis, in the county of Hennepin and State 5 of Minnesota, have invented certain new and useful Improvements in Folding Baby-Carriages; and I do hereby declare the following to be a full, clear, and exact description of the invention, such as will enable 10 others skilled in the art to which it appertains to make and use the same.

My present invention relates to improvements in baby carriages, and more specifically to folding running gears therefor, especially adapted to support a collapsible basket or hammock preferably of the type disclosed and claimed in my co-pending application filed May 21, 1919, under S. N. 298,718, and entitled "Baby-carrying basket."

To the above end, generally stated, the invention consists of the novel devices and combination of devices hereinafter described and defined in the claims.

25 In the accompanying drawings which illustrate the invention, like characters indicate like parts throughout the several views.

Referring to the drawings:

Figure 1 is a perspective view of the invention;

Fig. 2 is a fragmentary bottom plan view of the running gear, on an enlarged scale, with some parts shown in different positions by means of broken lines;

35 Fig. 3 is a plan view of one of the reach brackets with portions of the attached parts broken away;

Fig. 4 is a view partly in side elevation and partly in longitudinal section taken on 40 the line 3—3 of Fig. 3;

Fig. 5 is a detail view in section taken substantially on the line 5—5 of Fig. 3, on an enlarged scale; and

Fig. 6 is a side elevation, showing the running gear folded.

The folding running gear includes a reach 45 7, front and rear posts 8 and 9, respectively, a pair of reach brackets 10, two pairs of radius rods 11, front and rear pairs of stub 50 axles 12, wheels 13 journaled on said axles 12, and a pair of spreading toggles 14.

The reach 7, and posts 8 and 9, as shown, are preferably of tubular form, and the ends 55 of said reach and the lower ends of said posts, are pivotally connected to the reach brackets 10 by horizontal pins 15 and 16,

respectively. By reference to Fig. 4, it will be noted that the pivot pins 16 are located below and rearward of the ends of the reach 7, to permit the posts 8 and 9 to clear said 60 ends when in operative or upright positions, and to be folded into inoperative positions under the reach and into substantially parallel arrangement therewith.

The reach brackets 10 are provided with 65 horizontal inwardly projecting arms 17, and upwardly and outwardly inclined arms 18 in the form of inverted channels. The arms 17 straddle the reach 7 and thereby act as stops to limit the upward pivotal movements 70 of the brackets 10 on the reach 7, and the arms 18 are arranged to straddle the posts 8 and 9 and act as stops to limit the inward swinging movement of said posts and normally hold the same in diverging relation in 75 respect to each other. By causing the arms 17 and 18 to straddle the reach 7, and posts 8 and 9, said reach and posts are securely held against lateral twisting movement on their pivot pins.

To each arm 17 is intermediately secured 80 a clip 19 arranged to embrace the reach 7 and yieldingly hold the brackets 10 against pivotal movement thereon. Also secured to each arm 18 is a similar clip 20 arranged to 85 embrace the posts 8 and 9 and yieldingly hold them against pivotal movement on the brackets 10.

Formed with each pair of reach brackets 90 10 is a pair of downwardly and inwardly diverging arms 21 to which radius rods 11 are pivoted in pairs and quite close to the bracket 10. The pivots for the radius rods 11 are formed by bending their inner ends laterally downward to form short vertical 95 trunnions and inserting the same through seats in said arms and securing the same against removal therefrom, by cotter pins 22. The pivotal connections for the radius rods 11 are such as to permit swinging movement of each pair thereof toward and from 100 each other, and also to permit said rods to be folded into substantially parallel arrangement with the reach 7. Hook-like fingers 23, on the outer ends of the arms 21, afford stops to limit the outward swinging 105 movement of the radius rods 11. The outer ends of the radius rods 11 are connected to the inner ends of the stub axles 12 by vertical pivots 24, and the outer ends of the 110 spreading toggles 14 are connected by pivots 25 to the radius rods 11, inward of the pivots

24. Extensions 26 are formed on the outer ends of the spreading toggles 14 and are provided with depending cam pins 27 which work in slots 28 formed in laterally and inwardly projecting arms 29 on the inner ends of the stud axles 12. By reference to Fig. 2 it will be noted that the pivotal connection between the members of the spreading toggle 14 is slightly beyond a dead center, 10 and further outward movement thereof is prevented by the engagement of the cam pins 27 with the inner ends of the slots 28. The cam pins 27, by their engagement with the arms 29, securely hold the stub axles 12 15 against pivotal movement on the radius rods 11.

Obviously by buckling the spreading toggles 14, the radius rods 11 may be moved inward into substantially parallel arrangement with one another and the reach 7. This movement of the radius rods 11 also carries the wheels 13 into relatively close arrangement with each other, as shown by broken lines in Fig. 2. To complete the 25 folding of the running gear the posts 8 and 9 are swung outward and downward and then into overlapping position, the one with the other, and under the reach 7, as previously described. This folding movement 30 of the posts 8 and 9 will also cause the reach brackets 10 to swing on the pivots 15. When the running gear is thus folded, the same will appear as shown in Fig. 6.

35 Formed in the upper end of each post 8 and 9 is a hook 30, and secured to said posts slightly below the hooks 30. Also secured to each post 8 and 9 is a pair of upwardly diverging prongs 31 to the upper ends of which is secured a relatively short horizontal handle 32.

To lock the running gear against rolling movement, when left standing, there is secured to the rear rivets 25 a pair of lock fingers 33 arranged to be turned between 45 certain of the spokes of the rear wheels 13 to lock the same against turning movement. These fingers 33 may be swung inward under the rear spreading toggle 14, as indicated by broken lines in Fig. 2, when not in use. When the lock fingers 33 are set to lock the rear wheels 13, the same engage the ends of the stub axle arms 29 as stops, as shown in Fig. 2.

55 Removably suspended from the upper ends of the posts 8 and 9 is a collapsible baby carrying basket or hammock 34, previously referred to, and preferably made from canvas, or other suitable fabric, and has in its top and bottom marginal edges 60 metal reinforcing rods, not shown. A folding hood 35, is attached to the basket 34 and secured to the ends of said basket are buckle equipped hanger straps 36 having in their outer ends rings 37. These rings 37 are arranged to engage the hooks 30, and support

the basket 34 therefrom with freedom for lateral swinging movement. Secured to the intermediate portion of the basket 34, at the sides thereof, are two buckle-equipped retaining straps 38. Two upwardly diverging 70 buckle-equipped straps 39 are secured to the reach 7 and opposite sides of the basket 34 to limit the swinging movement thereof, or hold the same against swinging movement.

By unbuckling the straps 39, the basket 34 75 may be removed from the running gear by releasing the rings 37 from the hooks 30. The running gear may then be folded, as previously described, and secured in folded position by the sections of the straps 39 remaining attached to the reach 7.

The above described invention, while extremely simple, and of comparatively small cost to manufacture, has in actual usage, proven highly efficient for the purpose had 85 in view. When the running gear is folded the parts thereof are very compact and occupy comparatively little space so that the same may be readily taken into a street car, or other conveyance, while the basket with 90 the baby in it may be carried in the arms.

What I claim is:

1. A folding running gear comprising a reach, a pair of posts, brackets foldably connecting the posts to the reach, a pair of 95 radius rods foldably attached to each bracket, stub axles pivoted to the radius rods and having laterally projecting arms, wheels journaled on said axles, and a spreading toggle connecting each pair of radius rods and also having sliding pivotal connections with the respective pair of stub axle arms, in combination with a body attached to the posts.

2. A folding running gear comprising a 105 reach, a pair of posts, brackets foldably connecting the posts to the reach, a pair of radius rods foldably attached to each bracket, stub axles pivoted to the radius rods and having laterally projecting arms, 110 wheels journaled on said axles, and a spreading toggle connecting each pair of radius rods and also having sliding pivotal connections with the respective pair of stub axle arms, in combination with a body attached 115 to the posts, and a connection between the body and reach to prevent or limit the swinging movement of said body.

3. A folding running gear comprising a 120 reach, a pair of posts, brackets foldably connecting the posts to the reach, a pair of radius rods foldably attached to each bracket, stub axles pivoted to the radius rods and having laterally projecting arms, 125 wheels journaled on said axles, a spreading toggle connecting each pair of radius rods and also having sliding pivotal connections with the respective pair of stub axle arms, and a handle on one of said posts, in combination with a body attached to the posts. 130

4. A folding running gear comprising a reach, a pair of posts, brackets foldably connecting the posts to the reach, a pair of radius rods foldably attached to each bracket, stub axles pivoted to the radius rods and having laterally projecting arms, wheels journaled on said axles, and a spreading toggle connecting each pair of radius rods and also having sliding pivotal connections with the respective pair of stub axle arms, each of the posts being provided with a hook-like notch in its upper end, in combination with a body, and supporting straps for the body having rings detachably secured in said hook-like notches.

5. A folding running gear comprising a reach, a pair of brackets pivoted to the reach, a pair of posts pivoted to the brackets, stops on the brackets limiting their pivotal movement on the reach and the pivotal movement of the posts on the brackets into operative positions, clips yieldingly securing the brackets to the reach and the posts to the brackets against pivotal movement from operative positions, a pair of radius rods piv-

oted to each bracket for swinging movement toward and from the reach, stops limiting the outward swinging movement of the radius rods, stub axles pivoted to the radius rods and having laterally projecting arms, wheels 30 journaled on said axles, and a spreading toggle connecting each pair of radius rods and also having sliding pivotal connections with the respective pair of stub axle arms, in combination with a body attached to the 35 posts.

6. A folding running gear comprising a reach, a pair of posts, brackets foldably connecting the posts to the reach, a pair of radius rods foldably attached to each 40 bracket, stub axles pivoted to the radius rods, and means for holding the radius rods spread and the stub axles against pivotal movement.

In testimony whereof I affix my signature 45
in presence of two witnesses.

JULIUS A. MAHR.
